UNITED STATES PATENT OFFICE.

LEO ROSENMAN, OF NEWARK, NEW JERSEY, ASSIGNOR TO R. K. M. MFG. COMPANY,
A CORPORATION OF NEW JERSEY.

FASTENER STRIP OR FLY FOR GARMENTS.

Application filed May 12, 1922. Serial No. 560,405.

This invention relates, generally, to improvements in strips or flies to be used with garments; and, the present invention has reference, more particularly, to provide a novel construction of strip or fly, comprising a main base-strip of a strong or stout fabric and a facing of a delicate and more or less flimsy material, the strong or stout base-material having attached thereto an arrangement of metal fasteners, such as hooks and eyes, the fasteners being secured to the base-material by sewing, and the delicate facing at the same time serving as a means or covering to the line or lines of stitching so that the latter will not be exposed to view, when the strips or flies are attached to a garment.

The present invention has for its principal object to provide a strip or fly for garments having a facing of a delicate or flimsy material, and still permitting of the use of hooks and eyes therewith, whereby the strips or flies are adapted for use and attachment to the garment, without in the least destroying the usefulness of the delicate and weak fabric in connection with the strips or flies, as will hereinafter more fully appear.

The invention has for its further object to provide a novel method of folding the main base-member of a strong fabric and of the delicate and flimsy facing, the two fabrics being suitably secured together by a line of stitching, by means of which the hooks or eyes are also secured in place, and the facing being folded over the base-member, so that the line of stitching, and the exposed portions of the fasteners, when the strips or flies are attached to a garment, are hidden from view.

Other objects of the present invention not at this time more particularly enumerated will be clearly understood from the following detailed description of the present invention.

With the various objects of the present invention in view, the said invention consists, primarily, in the novel arrangements and combinations of the several devices and parts, all of which will be more fully described in the following specification, and then finally embodied in the claim which is appended to and which forms an essential part of the said specification.

The invention is illustrated in the accompanying drawings, in which:

Figure 1 is a face or plan view showing fragmentary portions of a pair of strips or flies, provided, respectively, with hooks and eyes, the said strips or flies being represented in their closed relation, edge to edge, and the various parts of each strip or fly being arranged according to and embodying the principles of the present invention.

Figure 2 is a similar view of said fragmentary portions of the two strips or flies, with the hooks and eyes thereof disconnected, said view illustrating more particularly the separable feature of the two strips or flies.

Figure 3 is a transverse vertical section taken on line 3-3 in said Figure 1; and Figure 4 is a similar section taken on line 4-4 in said Figure 1.

Figure 5 is a face or plan view of a portion of one of the said strips or flies, with the facing of a delicate material attached along one of its longitudinal marginal edges of the base-member of the strip or fly, showing the relative position of the said facing to said base-member before being folded over thereon; and Figure 6 is a transverse vertical section of the said base-member and facing, said section being represented as being taken on line 6-6 in said Figure 5.

Figure 7 is a transverse vertical section of a strip or fly comprising a base-member provided with both front and rear facing, but still embodying the principles of the present invention.

Similar characters of reference are employed in the said above described views, to indicate corresponding parts.

Referring now to the several figures of the drawings, the reference characters 1 and 2 indicate fragmentary portions of strips or flies, provided, respectively, with suitable hooks 3 and eyes 4, suitably secured to and connected with the base-members of the strips in a manner to be presently more particularly set forth.

As has been previously stated, each strip comprises a main base-member of a strong or stout fabric, as cotton, muslin, or the like, and a facing of a more delicate and flimsy nature, as silk, or the like. Now, it is a well-known fact, that as the delicate mate-

rial is insufficient in body to prevent the securing of the fasteners thereto, such as hooks and eyes, some means must be provided to which the fasteners can be secured, 5 so as to provide a strong and efficient strip or fly, which still has the appearance of being made of delicate material, as silk or the like.

To accomplish the objects of the present 10 invention, the main body or base-member of each strip or fly consists, essentially of an upper fabric-strip 5 and a lower fabric-strip, as 6, said strip 6 being longitudinally folded or doubled over, as at 7 and 8. The 15 previously mentioned facing of silk, or the like, is indicated by the reference-character 9, said facing being also longitudinally folded or doubled over, as at 10 and 11. To secure the fabric-strip or facing 9 to the 20 base-member, the longitudinal edge-portion 10 is placed between the upper fabric-strip 5 and the folded or doubled-over portion 7 of the lower fabric-strip 6, the various members then being secured together by means 25 of a row of stitching, as 12. The previously mentioned fasteners, as the hooks and eyes, are suitably disposed, at predetermined distances, between the portions 7 and 10 of the 30 respective members 6 and 9, the said fasteners being secured in place against displacement by means of the said row of stitching, as will be clearly evident from an 35 inspection of Figures 3 and 5 of the drawings.

After the facing-member 9 has thus been 40 stitched in place between the two fabric-strips 5 and 6, it is turned over the edge-portion 13 of the strip 5, so that it will lie directly upon and will cover the outer face 45 of said strip 5, substantially as shown in Figures 3 and 4 of the drawings.

It will be seen from an inspection more 50 particularly of Figures 1, 2 and 3 of the drawings, that the hook-shaped end-portions 45 of the hooks 3 extend beyond the marginal edge of the strip with which they are employed, while the hook-receiving portions of the eyes do not extend beyond the marginal edge of the other strip, with which 55 they are used. Thus, as will be seen from Figures 1 and 2, when the garment is worn, the corresponding marginal edges of the two strips will be brought in close abutting relation, whereby the fastening devices are entirely hidden from view.

If desired, the base member may have 60 secured thereto, in the manner of the present invention, in addition to the facing-member 9, a rear facing-member, as 17, both of 65 which front and rear facing-members are of a fabric of a delicate structure, such as

silk, or the like, as will be clearly evident from an inspection of Figure 7 of the drawings.

The finished strips or flies 1 and 2, thus 65 produced may be suitably attached to the garment 14 by disposing the edge-portions of the garment between the fold 8 of the strip-member 6 and the edge-portion 15 of the strip-member 5, the various parts being 70 united by a line of stitching, as 16.

From the foregoing description of the 75 present invention it will be seen, that a simple, neat, and well-appearing strip or fly for garments has been produced, which has the 80 appearance of being made of a fabric of a delicate structure, such as silk, and in which the fasteners, as hooks and eyes, instead of being fastened directly to the delicate fabric, are secured directly to a strong fabric, 85 such as cotton, linen, or the like, so that the strip or fly can be sewed in position upon a garment, without the least danger, when in use, of the fasteners pulling away from their fixed positions upon the strip or fly. 90

I claim:—

Flies for garments comprising a pair of 95 fastener strips, each strip consisting of a main base-member made up of an upper and a lower element, and a facing-member, having a marginal fold disposed between said upper and lower elements, and the main portion of the facing-member being disposed upon the outer face of the upper element of said base-member, garment hooks 100 arranged between the fold of the facing member and the lower element of the base-member of one of said fastener-strips with their hook-shaped portions projecting beyond the marginal edge of the fold of said strip, eyes arranged between the fold of the 105 facing member and the lower element of the base-member of the other of said fastener strips at points so that the eyes will not project beyond the marginal edge of the fold 110 of said last-mentioned fastener-strip, and lines of stitching for securing said facing members, said lower and upper elements and the garment fasteners of the respective fastener-strips in assembled relation, said upper and lower elements, furthermore, being 115 made of a fabric of greater strength than the facing members, all arranged to prevent pulling away of the garment-fasteners from said strips, and to hide said fasteners from view when the marginal edges of the folds of said strips are brought into abutting relation.

In testimony that I claim the invention set forth above I have hereunto set my hand this 10th day of May, 1922.

LEO ROSENMAN.
